UNITED STATES PATENT OFFICE

2,449,873

SUN SUIT TYPE OF APPAREL

George Brockman, New York, N. Y.

Application April 8, 1947, Serial No. 740,027

2 Claims. (Cl. 2—80)

1

The invention relates to apparel for juveniles, and particularly to sun suit types of apparel.

Pursuant to the invention the apparel comprises "shorts" formed of integral fabric providing front and rear panels of like configuration, the "shorts" being closed at their respective meeting lateral margins by buttons and buttonholes or equivalent readily attachable elements, the crotch portion of the material connecting the front and rear panels being cut to assume an upwardly concave formation, when the lateral margins of the front and rear panels are closed.

The "shorts" may be supported upon the body of the wearer, as may be desired, but preferably by means of shoulder straps. Desirably, a front waist or apron may be secured to upper margin of the front panel, and the front ends of the straps secured to the margin of such waist or apron.

Among the advantages resulting from the invention are the artistic design of the apparel, simplicity of assembly upon the body of the wearer, and ready washability and laundering of the "shorts" upon opening the front and rear panels.

Further features and objects of the invention will be more fully understood from the following detailed description and the accompanying drawings, in which:

Fig. 1 is a front elevation of a sun suit embodying the invention;

Fig. 2 is a rear elevation of Fig. 1;

Fig. 3 is a side view of Fig. 1;

Fig. 4 is a detail sectional view on line 4—4 of Fig. 1 on an enlarged scale;

Fig. 5 is a plan view of the sun suit of the preceding figures showing the pattern thereof, and

Fig. 6 is a detail sectional view taken on line 6—6 of Fig. 5.

Referring to the drawings, the illustrated apparel, designated 10, is typical of a sun suit for juveniles.

In general, the apparel includes "shorts," designated generally 11, comprising a front panel and a rear panel connected integrally with one another, as appears more fully hereinafter, the upper margin of the front panel is secured to a waist or apron portion 12. As shown, the apparel is suspended from the shoulders of the wearer as by means of straps 13, 13, each advantageously secured at its fixed end 13b at the upper margin of the rear panel of the "shorts" 11; the free end 13a of each strap is suitably secured to the upper portion of the waist or apron portion 12, as by means of buttons 14 and buttonholes 15.

A particular feature of the invention resides in the construction of the "shorts" 11, being of integral material extending from its front upper margin 11a to its rear upper margin 11b, and the contour of the material cut and bound by edg-

2

ing material 16 to provide the upwardly extending concavely arcuate crotch formation indicated at 17, the material of the crotch portion interconnecting the front and rear panels. By such concavely arcuate formation of the crotch portion, the lower opposite side portions of the material of the front and rear panels assume a true circular contour embracing the upper portions of the legs of the wearer, and free of the legs when the wearer assumes normal standing and walking positions. Furthermore, the cut of the material, the positioning of the edging material and the stitching about the crotch is such that, when the front and rear panels are brought together to form the shorts, the crotch is bowed forwardly to give greater room at the forward part of the lower body. See Fig. 3.

The "shorts" are closed by closure of the respectively aligned lateral margins 11c, 11c of the front and rear panels, as by suitable fastening devices, preferably buttons 18 and buttonholes 19.

I claim:

1. A sun suit for juveniles including "shorts" comprising a front panel, a rear panel, a unitary crotch connecting said front panel and said rear panel, means joining side edges of said front panel to side edges of said rear panel to form the "shorts," and edging material binding the edges of said panels and said crotch, the contour in which the material of the "shorts" is cut and the binding of said edging material providing an upwardly extending concave crotch formation and bowing said crotch forwardly of the "shorts" to give greater room to the lower forward part thereof.

2. A sun suit for juveniles including "shorts" comprising a front panel, a rear panel, a unitary crotch connecting said front panel and said rear panel, button-and-button-hole connections joining side edges of said front panel to side edges of said rear panel to form the "shorts," and edging material binding the edges of said panels and said crotch, the contour in which the material of the "shorts" is cut and the binding of said edging material providing an upwardly extending concave crotch formation and bowing said crotch forwardly of the "shorts" to give greater room at the lower forward part thereof.

GEORGE BROCKMAN.
